PULASKI D. WESCOTT, OF CORNING, NEW YORK, ASSIGNOR OF TWO-FIFTHS TO TALCOTT W. TANNER, EDWIN J. CARPENTER, WILLIAM N. KING, AND EDWIN E. CUDDEBACK, OF SAME PLACE.

ACETYLENE-GAS GENERATOR.

SPECIFICATION forming part of Letters Patent No. 634,434, dated October 3, 1899.

Application filed June 8, 1898. Serial No. 632,884. (No model.)

To all whom it may concern:

Be it known that I, PULASKI D. WESCOTT, a citizen of the United States, residing at Corning, in the county of Steuben and State 5 of New York, have invented a new and useful Improvement in Acetylene-Gas Generators, of which the following is a specification.

My invention relates to improvements in acetylene-gas generators in which the carbid 10 is delivered from the carbid-receptacle to the water in the water-receptacle; and the objects 15 of my improvements are, first, to provide means whereby the carbid shall be delivered automatically to the water and in such a manner 20 that the carbid will be completely decomposed during its descent through the water; second, to provide means for feeding the carbid which 25 will not become clogged or otherwise obstructed, and, finally, to provide means for cleaning out the waste products of decomposition and 30 renewing the carbid charge without the escape of gas from the generator or the admission of air thereto. I accomplish these objects by 35 the apparatus shown in the accompanying drawings, in which—

Figure 1 is a vertical transverse section of the apparatus; Fig. 2, a plan view, and Figs. 3 and 4, details of the feed mechanism.

Similar letters refer to similar parts throughout the several views.

A represents the shell of a gasometer supported upon the legs *a a a* and within which is an inner wall *A'*. The bell of the gasometer *B* has its outer wall located between the 35 walls of the gasometer *A A'* and its inner wall within a chamber surrounding the stand-pipe *C*. This stand-pipe *C* rises from the base of the gasometer, where it is enlarged to form the chamber *E*. Chamber *E* is provided with 40 a conical bottom and connects by a short neck *e* with a second chamber *F*, located below the bottom of the gasometer, which I term the "cleaning-chamber." The top of the stand-pipe *C* is enlarged to form a gas-chamber *D*, 45 which is provided at the top with a hand-hole closed by the cap *d*. Within the chamber *D* is located the carbid-receptacle *G*, said receptacle being movable vertically within the chamber and supported upon a tubular col-

umn or stem *g*, which extends downward 50 through the stand-pipe *C*, chamber *E*, and chamber *F*, a stuffing-box *s* being provided where the stem *g* passes out from the bottom of the chamber *F* and a guide *c* being provided in stand-pipe *C*. A valve *g'*, in the 55 form of a double cone, is fastened to the stem *g* to close the passage *e* from the chamber *E* to chamber *F*. Within the carbid-receptacle *G* is the piston or plunger *H*, which fits loosely within the cylinder. The piston-rod *h* passes 60 from this piston down through the tubular stem, this projecting portion of the rod *h* being cut to form a series of teeth, as shown. A stuffing-box *s'* at the head of the tubular stem *g* makes a tight joint at this point. A 65 lever *I*, pivoted at *i* to an arm extending down from the bottom of chamber *F*, is coupled to the end of stem *g* for the purpose of raising and lowering said stem. Two levers *J J*, 70 coupled together at *j* and pivoted to the swinging fulcrum-bars *j' j'*, which are hung from the bottom of chamber *F*, have their outer ends coupled by connecting-rods *K K* with the arms *b b*, projecting out from the top of the bell *B*. Pawls *l l* are pivoted to the levers *J J* where they are joined together, said 75 pawls being adapted to engage the teeth on the rod *h*, the details of construction at this point being shown in Figs. 3 and 4. Holes in levers *J J* allow for the adjustment of the fulcrum-points to regulate the feed. A dog *m* is coupled to the end of stem *g* and is adapted to swing in and engage the teeth of the rod *h* to prevent the descent of said rod when the pawls *l l* are being dropped down for new 80 engagement with the teeth on said rod. Three vertical pipes *L L' L''* extend up from the bottom of the gasometer and are provided with inwardly-extending arms, which are fastened to the top of chamber *D*, these three 85 upright pipes forming guides for the bell *B* of the gasometer, which is provided with suitable rollers, and also forming a support for the chamber *D*. One of said pipes *L* opens into the chamber *D* at the top and is carried 90 around at the bottom and up into the gasometer within the inner shell *A'*. One of the remaining pipes *L'* is also carried around and 95

up into the gasometer and is provided at the top with an offshoot, which runs to the service-pipes. A filler-pipe M connects with the neck e and extends upward to a desirable height above the stand-pipe C. A draw-off cock O is provided at the bottom of chamber F.

In operation, the receptacle G being filled with broken carbid and the stand-pipe and chambers of the gasometer with water, as indicated, the bell B is drawn up and then allowed to descend. This descent of the bell operates the levers J J through connecting-rods K and causes the pawls l l to grip the rod h and force it upward. This causes the piston H to lift the carbid in the receptacle G, causing the topmost lumps to roll over the edge of the receptacle and descend into the water in the stand-pipe C. A conical deflector d' is attached to the plate d to facilitate this discharge of the carbid. As the lumps of carbid descend through the water in stand-pipe C decomposition takes place, and by the time the lumps have descended through the length of the stand-pipe they will have been completely decomposed and nothing but the lime residue will accumulate on the bottom of chamber E. The gas rises through chamber D, coming in contact with the fresh carbid delivered from receptacle G, any moisture arising with the gas being taken up by this fresh carbid, and the gas passes down through pipe L and up into the bell of the gasometer. If it is desired to wash the gas, the arm of the pipe L within the gasometer may be turned downward, as indicated by the broken lines. As the gas is formed it accumulates in the bell and causes it to rise. The gas is taken off through the pipe L' according to the demand of consumption. As the gas is consumed the bell B will drop, causing a new upward movement of the piston H and a fresh delivery of carbid to the stand-pipe. Thus the rise and fall will cause the carbid to be automatically fed to the stand-pipe in the proper quantity.

When the carbid in the receptacle G has been exhausted and it becomes necessary to renew the charge, the lever I is thrown down, causing the stem g to rise and with it the receptacle G. The top of said receptacle is brought up against the top of chamber D, where a packing-gasket is located to make a tight joint. The plate d may then be taken off without escape of gas from chamber D or the admission of air thereto. The dog m and the pawls l l are thrown out of engagement with rod h and said rod allowed to drop down until the piston H rests upon the bottom of receptacle G. The receptacle G is then filled 55 with a fresh supply of broken carbid, after which the plate d is replaced and secured against the head of chamber D. The lever I is thrown up, and the apparatus is ready for a fresh generation of gas. When the stem g is raised, the valve g' will also be lifted, allowing the lime accumulated in chamber E to descend into chamber F. While this valve

is open the water in the stand-pipe C, which has been taken up by the decomposition of the carbid, may be renewed through the filler-pipe M, the water being brought to the proper level, as indicated in Fig. 1. When the lever is thrown up and the valve g' is closed, the lime deposit which has descended into chamber F may be drawn off through cock O without fear of escape of gas from or admission of air to the generator. Preferably I partially fill the carbid-receptacle G with kerosene or other liquid which does not combine with the carbid in order that when the receptacle is to be charged a minimum quantity of gas will be left in said receptacle in place of the discharged carbid, and no air will remain in the receptacle after it has been recharged. This liquid filling would descend 85 below the piston H as it rises, since the piston does not fit the receptacle closely. The projecting point d' will also displace a quantity of the gas when the receptacle is thrown up.

Variations may be made in the manner of 90 constructing and operating the several parts of the apparatus without departing from the spirit of my invention. For instance, it will be readily apparent that the piston H might be held stationary and the receptacle G made 95 to descend by the ratchet-gearing, so as to deliver the carbid over its top instead of lifting the carbid, as herein shown in my preferred construction.

I am aware that heretofore generators have 100 been made in which the carbid is dropped into the water from the bottom of the carbid-receptacle. In this arrangement, however, a valve or other cut-off is required to regulate the discharge of carbid, and the probability 105 of such valve or cut-off becoming clogged or otherwise obstructed, so as to render the generator inoperative or very uncertain in its operation, is strongly against such construction. I avoid this difficulty by delivering the carbid from the top of the receptacle, thus dispensing with the objectionable valve or other cut-off.

Having thus described my apparatus, what I claim as my invention, and desire to secure 115 by Letters Patent, is—

1. In an acetylene-gas generator, the combination of a water-chamber, a carbid-receptacle adjacent the water-chamber, and means for feeding the carbid from the top of the receptacle, substantially as described.

2. In an acetylene-gas generator, the combination of a water-chamber, a gas-chamber above the water-chamber, a carbid-receptacle within the gas-chamber, and means for lifting the carbid in the receptacle, whereby it is fed over the top of the receptacle and dropped into the water in the water-chamber below.

3. In an acetylene-gas generator, the combination of a water-chamber, a gas-chamber above the water-chamber, a carbid-receptacle within the gas-chamber, means for lifting the carbid in the receptacle, means for raising

- and lowering the receptacle, and a hand-hole in the head of the gas-chamber above the receptacle.
4. An acetylene-gas generator comprising two adjacent receptacles, one for containing water and the other for carbid, a piston movable within the carbid-receptacle, and means for raising the piston controlled by the amount of stored gas on hand.
5. In an acetylene-gas generator, the combination of a water-chamber, a gas-chamber above the water-chamber, a carbid-receptacle within the gas-chamber, a piston within the receptacle, a gasometer, and rod and lever connections between the piston and gasometer, whereby the rise and fall of the bell will operate to elevate the piston.
6. In an acetylene-gas generator, the combination of a stand-pipe constituting a water-chamber, a gas-chamber at the top of the stand-pipe, a carbid-receptacle within the gas-chamber, means for feeding the carbid from the receptacle, whereby the carbid is delivered to the water in the stand-pipe and completely decomposed in its descent through the stand-pipe, and means for drawing off the products of decomposition from the bottom of the stand-pipe.
7. In an acetylene-gas generator, the combination of a water-chamber comprising an enlarged base portion and a stand-pipe rising above said base portion, a cleaning-chamber below the water-chamber, a gas-chamber at the top of the stand-pipe, a hand-hole in the top of said chamber, a carbid-receptacle within the gas-chamber, a column supporting the receptacle, said column passing down through the water-chamber and the cleaning-chamber, a valve on the column to close communication between said chambers, and means for raising and lowering the column and receptacle for the purposes set forth.
8. In an acetylene-gas generator, the combination of a gasometer, a water-chamber, a gas-chamber above the water-chamber in communication with the gasometer, a carbid-receptacle supported within the gas-chamber, a piston within the receptacle, a rod from said piston extending down below the water-chamber, a lever pivoted below the water-chamber having a pawl to engage teeth on the piston-rod, a connecting-rod between the lever and gasometer-bell, and a dog to engage and hold the piston-rod after it has been actuated by the rise of the bell.
9. In an acetylene-gas generator, the combination of a gasometer, a stand-pipe rising from the center of the gasometer, an enlarged chamber at the base of the stand-pipe, a cleaning-chamber in communication therewith positioned below the gasometer, a gas-chamber at the top of the stand-pipe, a carbid-receptacle within the gas-chamber, a tubular column to support said receptacle passing down through the stand-pipe and cleaning-chamber, a lever to raise and lower said column, a valve on the column to close the passage into the cleaning-chamber, a piston in the carbid-receptacle, a piston-rod passing down through the tubular column and terminating in a serrated extension, a pair of levers coupled together in axial alinement with said extension, swinging fulcrum-bars for said levers, connecting-rods uniting the levers with the gasometer-bell, pawls on the levers to engage the teeth on said extension, and a retaining-dog hung at the end of the tubular column, together with the charging and discharging passages and gas connections, substantially as described.
- In testimony whereof I have affixed my signature in presence of two witnesses.
